UNITED STATES PATENT OFFICE

FRANK D. GIDDINGS, OF FORT COLLINS, COLORADO

GRINDING MACHINE

Application filed August 19, 1929. Serial No. 386,895.

This invention relates to reducing mills for farm products such as corn fodder, hay, grain, beet tops, ensilage and foliage in general.

5 It is an object of the invention to provide a mill of simple construction which in a single action cuts and grinds material of the above stated nature uniformly to any desired fineness.

10 Another object is to provide a mill capable of reducing farm products that are wet, as easily and as completely as those that are in a dry condition.

15 A further object is to provide in a mill of the above described character, a positive and continuous feed of material to the cutting and grinding element.

20 Another object resides in providing means for the ejection of obstructive objects in the feed, without injury to the cutting and grinding members, and still further objects reside in many novel features of construction and many novel arrangements and combinations of parts all of which contribute to provide a 25 machine in which simplicity of construction is combined with durability and with practicability and efficiency in use.

20 In the accompanying drawings in the several views of which like parts are similarly designated,

30 Figure 1 represents a side elevation of the mill,

35 Figure 2, a plan view of the mill, drawn to a larger scale, the cover of the grinding and cutting element having been shown in the open position and the end part of the feed element having been omitted,

40 Figure 3, a longitudinal vertical section through the machine, taken on the line 3—3, Figure 2, and drawn to a somewhat reduced scale,

45 Figure 4, an enlarged elevation of one of the grinding members of the cutting and grinding element of the mill,

50 Figure 5, a section on the line 5—5, Figure 4,

55 Figure 6, an enlarged fragmentary section of a part of one of the heads of the grinding and cutting element, showing the method of

mounting the cutting members and grinding members of the same,

Figure 7, a sectional plan view of the parts shown in Figure 6,

55 Figure 8, a reduced side elevation of the machine, and

Figure 9, a section taken on the line 9—9, Figure 6.

60 The drawings above briefly described illustrate a construction which has proven advantageous from all standpoints of manufacture and use and while this construction will be herein specifically explained it is to be understood that within the scope of the invention claimed, numerous variations may be 65 made.

70 The mill comprises a truck 5 supported on wheels 6 and capable of self-propulsion or of being hauled to a place of operation by a tractor or by draft animals.

75 The truck supports a grinding element, a feed element including a laterally projecting endless belt 7 onto which the material to be ground is fed, and a fan 8 which draws the product of the grinding element through an upright pipe 9 into an elevated bin 10 from which it is delivered to wagons or other receptacles by means of an inclined chute 12.

80 The various elements are driven from an engine 13, likewise mounted on the chassis of the truck. The reducing element and the feed element and the shaft, pulleys and other gearing by which they are connected with the engine, are assembled on a main frame 14 that is mounted at the end of the truck chassis and projects laterally therefrom.

85 The frame includes the side plates 15 of the grinding and cutting element, the therewith connected wings 16 between which the rollers comprised in the feed element are supported, and the forward projecting arms 17 which provide a fulcrum for the yielding frame of the endless apron 7 included in the feed element.

90 The rotor of the fan and the rotor of the grinding and cutting element are mounted directly on the engine shaft 18, as clearly shown in Figure 2.

95 The grinding element comprises a housing 100 of which the side plates 15 are parts.

The housing provides a cylindrical chamber 19 for the rotor of the grinding and cutting element and the circumferential wall of this housing includes a stationary part 20 and a hinged cover part 21 which when opened affords access to the interior of the housing.

The grinding and cutting chamber proper is defined by two arcuate screen plates 22 and 23 in circular alignment which are supported in slide-ways on the side plates of the housing.

When the cover is opened these two screen plates may be separately removed by merely 15 sliding them through the ends of their respective ways, it being understood that one of the plates is mounted on the sides of the cover and the other plate on the sides of the stationary part of the housing.

20 The ends of the screen plates are spaced apart at the side of the housing at which the material is fed into the grinding chamber to provide a feed opening 24. Part of this opening is normally closed by a sectional cover, 25 the sections of which are hinged to move about a common axis.

30 The cover sections 25 are held in their closed position by shearing pins 26 made of frangible material and inserted in registering holes of flanges 27 of the cover sections and a cross bar 28 on the stationary housing of the grinding element.

35 When in the operation of the mill a bolt or other hard object enters the grinding chamber, the pressure exerted thereby upon one or more of the cover sections during rotation of the rotor, breaks the respective shearing pin or pins with the result that the cover members are thrown outwardly and enlarge the 40 feed opening sufficiently for the discharge of the obstructive objects without damage to the cutting and grinding members of the mill.

45 At the lower ends of the cover sections, are knives or cutting blades 29 that cooperate with other blades on the rotor of the crushing and grinding element to reduce the material entering the grinding chamber through the feed opening.

50 The rotor is composed of a number of heads 30 mounted adjointly on the shaft of the cutting and grinding element, which as stated before, is a continuation of the motor shaft 18. The heads provide a cylindrical circumferential surface broken by gaps 31 and the cutting edges of knives 32 mounted 55 upon the circumference of the cylinder project over the edges of these gaps to cooperate with the relatively stationary cutting blades 29.

60 Referring particularly to Figures 6 and 7 of the drawings, the heads 30 are provided with recesses 33 which are spanned by the knives 32 that rest upon the outer edges 34 of the same. Bolts 35 secure the knives to the 65 heads and screws 36 passing through open-

ings of the knives and bearing against the surface of the recesses, together with nuts 37 on the screws bearing on the outer surfaces of the knives serve to adjust the position of the knives so as to regulate the distances of their cutting edge from the edges of the stationary cutting blades 29.

70 In the construction shown in the drawings, each head carries two knives and the heads are relatively arranged to place the knives in advance of each other with relation to the direction of rotation of the rotor, as shown in Figure 2.

75 Arranged upon the peripheral surface of the heads between the recesses over which the knives project, are pluralities of cutting and grinding studs 38 which are placed in staggered relation to each other so as to cover the entire width of the head. The studs thus arranged, distribute the material transversely 80 of the grinding chamber in the path of the cutting edges of the knives.

85 The studs are formed, as best shown in Figures 4 and 5, with an angular shank 39 and a flaring or beveled head 40, the sides of which 90 are serrated to form teeth 41 which cut the material to a finer size after it has been reduced by the knives. The main object of the studs, however, is to grind the material against the screens to a fineness that permits 95 it to pass through the perforations of the same.

98 The material thus discharged from the grinding chamber falls in a sump 42 at the lower portion of the housing from where it is 103 drawn by the action of the fan to be ultimately discharged through the spout 9 into the bin 10 and thence through the trough 12 into wagons or other receptacles.

108 The studs are supported in V-shaped pockets 43 at the sides of the heads and they are held against displacement under centrifugal force by U-bolts 44 extending through 113 openings in the head and secured by nuts 45. The U-bolts engage in grooves 44a in the shanks of the studs and thus lock the studs in place.

118 In the operation of the mill the cover 21 is in the closed position in which its screen section is continuous with that of the stationary 123 portion of the housing and the cover is locked in place by latches 46 on the stationary part of the housing, engaging with headed pins 47 on the cover, as shown in Figure 1.

128 The feed element by which the material is fed into the feed opening of the cutting and grinding element comprises the before mentioned endless carrier 7, a drum 48 equipped with mechanically projected impelling fingers 49, a peripherally ribbed roller 50 and a 133 peripherally smooth roller 51.

138 The drum and the two rollers are arranged at different distances from the feed opening, the smooth roller being nearest to the same and the drum and the rollers are also posi-

tioned at gradually decreased distances from the apron in the direction of the opening.

The drum has peripheral ribs 52 and the fingers extend laterally from shafts 53 that are rotatably mounted in bearings 54 between the ribs.

The shafts have at one end, a crank arm 55 extending across an end of the drum and during rotation of the drum these arms engage with a stationary cam 56, best shown in Figure 3, to cause rotation of the shafts for the purpose of projecting the fingers radially from the periphery of the drum.

The fingers at the ascending side of the drum lie against the peripheral surface thereof in seats at opposite ends of the ribs, but at the descending side of the drum they are projected outwardly from the drum.

The apron or carrier 7 mounted upon sprocket wheels 57 and 58 on shafts at opposite ends of a yielding frame 59 which is fulcrumed at 60 on the ends of the arms 17 of the main frame of the machine, travels in the operation of the mill in the direction of the feed opening.

The fingers on the rotating drum 48 impel the material into the space between the apron and the peripherally ribbed roller 50, and the latter causes the material to advance through the narrower space between the peripherally smooth roller 51 and the apron, toward and through the feed opening of the cutting and grinding chambers.

The frame 59 of the apron is at its end remote from the fulcrum, suspended from a stationary cross bar 61 of the main frame by coiled springs 62 and these springs permit of a yielding movement of the frame under pressure of the material passing between the apron and the rollers.

It will be readily seen that the feed element as described, insures a positive and substantially constant and uniform movement of material fed onto the apron, into and through the feed opening of the grinding chamber.

A line shaft 63 mounted in bearings 64 on the arms 17, is driven from the engine shaft 18 by means of a belt 64, the pulley 65 on the line shaft being larger than the pulley 66 on the engine shaft and loosely mounted.

A clutch 67 on the line shaft, moved by a hand lever 68, establishes the rotative continuity of the pulley 65 and the shaft 63 and the pulley acts as a fly wheel to assist in the uniform motion of the different elements of the machine.

A stub shaft 69 is driven from the line shaft at a reduced speed by means of a sprocket chain 70 and a gear wheel 71 on the stub shaft meshes with a smaller gear wheel 72 on the shaft of the smooth roller 51 of the feed element.

The peripherally ribbed roller 50 is driven from the smooth roller by means of a sprock-

et chain 73 and the finger carrying drum 48 is driven from the ribbed roller 50 through the medium of a sprocket chain 74. The rearward shaft of the apron receives its motion from the line shaft by means of a sprocket chain 75.

It is to be observed that the roller 50 rotates at slower velocity than the smooth roller 51, that the finger-carrying feed drum 48 moves slower than the ribbed roller 50, and that the drum and the rollers move faster than the endless apron. Plates 76 on the underside of the hinged cover sections prevent the material from moving upward with the roller.

Flaring boards 77 at opposite sides of the apron frame provide together with the upper surface of the apron, a trough into which the material is fed and the apron may be composed of lapping slats mounted on parallel sprocket chains on the sprocket wheels of the apron.

The boards 77 at their ends adjacent the roller 48, flare inwardly as at 77a and adjoin corresponding flaring parts of the wings 16 of the main frame thereby forming a constricted throat through which the material must pass into the space between the wings.

The fingers 49 on the roller draw the material into said space and this arrangement not only prevents spilling, but also increases the capacity of the machine.

The construction of the rotor of a series of heads assembled on the same shaft, permits of varying the width and capacity of the mill by merely changing the number of the heads and proportioning the grinding chamber and other parts of the machine accordingly.

The sliding screens that define the grinding and cutting chamber, are readily interchanged with screens of different mesh to vary the fineness of the product of the cutting and grinding actions.

It will be seen from the foregoing that I have made novel provision for carrying out the objects of the invention and attention is again invited to the fact that within the scope of said invention as claimed, numerous variations may be made.

What I claim and desire to secure by Letters Patent is:

1. In a mill of the character described, a reducing element comprising a reduction chamber having a feed opening, a cutting blade at an edge of the feed opening, a rotor in the chamber having a peripheral recess, a cutting member resting upon an edge of the recess and capable of movement about said edge to vary the distance of its cutting edge from the axis of rotation of the rotor, and screw means to adjust the cutting member by its said movement and to hold the same in an adjusted position.

2. In a mill of the character described, a

reducing element comprising a chamber having a perforated wall and a feed opening in the wall, a cutting blade at an edge of the feed opening, a circular head in the chamber, having peripheral recesses, and pockets between the recesses, knives on the head projecting across edges of the recesses, studs resting in the pockets and projecting beyond the periphery of the head, and means to lock the studs against lateral and longitudinal displacement.

In testimony whereof I have affixed my signature.

FRANK D. GIDDINGS.
